UNITED STATES PATENT OFFICE.

JOSEPH R. LANCASTER, OF NEW YORK, N. Y., ASSIGNOR TO JORDAN L. MOTT, OF SAME PLACE.

DESIGN FOR SINK.

Specification forming part of Design No. **7,465**, dated June 2, 1874; application filed May 1, 1874.
[Term of Patent 7 years.]

To all whom it may concern:

Be it known that I, JOSEPH R. LANCASTER, of the city, county, and State of New York, have invented a new and original Design for a Sink, of which the following is a specification:

The design relates to the exterior ornamentation of the sides of the sink, and to both the form and ornamentation of the legs, back, and water-pipe, the base of the delivery-cock, and an air-chamber connected therewith, as shown in accompanying printed illustration.

The sink G is of an old or well-known shape. Below the edge or shoulder *a* the ornamentation is mosque in style, consisting of a relief of leaves, curved and joined at their bases. Above the ledge *a* the ornamentation is composed of separated facets or rectangular figures, which may have either a plain or a figured surface, as preferred. The legs D are fluted in the middle part, and enlarged and ornamented by leaf-like reliefs above and below the same. The upper part of the legs resemble the heads of certain architectural columns, being composed of a series of astragal moldings surmounting

a fluted or grooved section. The back E of the sink is a flat vertical plate, with a molded edge or margin, which is straight in the upper part, while the sides have an irregular outline, composed partly of straight and partly of curved lines. The water-pipe F is a short fluted column, the base G of the cock is grooved around the edge, and the air-chamber H is conical or hemispherical in form, with a series of bands radiating from the center.

What I claim is—

1. The design for the ornamentation of the sides of the sink, as shown.
2. The design for the form and ornamentation of the legs, as shown.
3. The design for the form and marginal ornamentation of the back E, as shown.
4. The design for the form and ornamentation of the water-pipe, cock-base, and air-chamber, as shown.

JOSEPH R. LANCASTER.
